YARN MAKING APPARATUS

Application filed May 6, 1929. Serial No. 360,980.

This invention relates to improvements in yarn making apparatus and is directed more particularly to spindles for use in connection with such apparatus.

Among the principal objects of the invention is the provision of spindle apparatus which is efficient in operation and economical to manufacture, the novel features and advantages pertaining to which are hereinafter more fully described and illustrated in the accompanying drawing in which the figure is a side elevational view of a spindle construction partly in section which embodies the features of the invention.

Referring to the drawing, the invention will now be described in detail.

A base or rail 2 is shown which may represent the side rail of a spinning frame or the like which is adapted to support the apparatus of the invention. A member 4 is secured to the rail after the manner shown for rotatably supporting a spindle. The member 4 is preferably in the form of a cup or tubular in shape so as to provide a skirt or annular wall 4'. A lower hollow spindle 6 extends upwardly within the cup and passes through the lower wall for securing the cup and spindle to the rail as shown. In this way the spindle and cup are held against rotation. The spindle comprises an upper hollow spindle 8 which is preferably tapered for receiving a spool or bobbin 10 (shown in dotted lines) and is integral with a pulley 12. A hub 13 extending downwardly from the pulley is rotatable on the non-rotatable spindle 6. Corresponding tapering surfaces 14 provided between said hub and spindle 6 serve to support the spindle 8 and pulley for rotative movements on the spindle 6. An annular recess 15 is provided in the pulley around the hub.

As will be seen the spindle 6 extends upwardly into the hub of the pulley while the hub 13 extends downwardly into the cup 4 whereby a bearing is provided for the rotative spindle which is of substantial length. Also it will be noted that the bearing extends into the pulley so as to be capable of withstanding any pulling strains of a belt engaging the pulley. The lower end of the spindle 8 and

the upper end of spindle 6 are arranged to interfit so as to provide a continuous opening up through both spindles. The spindle 8 and pulley are removable upwardly from off the lower spindle 6. The cup 4 is arranged to function as a reservoir for lubricant so that the bearing surfaces are well lubricated at all times. By partly filling up the cup with lubricant and dropping the rotatable parts into place the likelihood of lubricant flowing outside the cup is obviated which is of course objectionable in connection with this class of apparatus. A groove may be provided along the spindle to facilitate the proper lubricating of the parts. As will be seen the inner diameter of the cup increases towards the lower end because the side walls are tapering.

The spindle 8 at its upper end receives a tension device represented in general by T. This in detail comprises a central collar 18 which is provided with a tapered opening to fit the tapered spindle whereby it may be frictionally held by the spindle for rotation and yet be removable therefrom. This collar is provided with a lower flange 19, screw threads thereabove and a longitudinal key way 20 all as shown. A tension hub 22 provided with a yarn receiving eye 24 in the outer end thereof is rotatable on said collar and rests on the flange 19 thereof. A washer 26 slidable along the threaded portion of the collar 18 is held against rotation thereon by an indent 28 which engages slot 20. A spring 30 disposed between the member 26 and a nut 32 in threaded engagement with the collar is adjusted by screwing the nut along the collar. This spring urges the parts into frictional engagement.

In operation the pulley 12 and spindle 8 are rotated by a driving belt passing around the pulley in the usual way. A central yarn or cord is led up through the hollow spindles and yarn from the spool 10 is led through the opening 24 in the tension arm 22 and onto said yarn or cord so that as the spool is rotated the yarn from the spool is wound around the core. The arm 22 is by means of the spring and associated parts frictionally clutched to the spindle so that according to

the tensioning of the spring more or less tension may be applied to yarn unwound from the spool.

By reason of the frictional action the arm does not overtravel the spindle or spool and the yarn passing therethrough is not loosened but instead is maintained taut at all times.

As one feature the tension mechanism may be readily removed from the spindle to facilitate the changing of spools.

A rod 40 carried by the support 2 has on its upper end a bracket 41 which has fixed thereto by means of a hollow bolt 44 a yarn guide cap 42. The central cord mentioned passes through the hollow bolt for the winding operation. As the spindle rotates, the yarn from the spool which passes through the tension arm is guided by the peripheral edge of the wall of the cap onto the cord. The shell 20 holds the yarn in a comparatively small radius during operation so that it will not loop outwardly and become tangled when the spindle and spool is stopped.

As will be seen, I have provided apparatus wherein a rotatable spindle and a non-rotatable spindle are arranged whereby one supports the other and which are separable. Also it will be noted that a bearing is provided which extends upwardly into the pulley while the parts are arranged to facilitate the lubrication of the parts without danger of dripping onto the yarn. As a further feature it will be noted that the tension device is adapted to tension the yarn to obtain various tension effects while the same is readily separable from the spindle.

I am aware that many changes may be made in the form of the invention without departing from the scope of the invention, 40 and I therefore prefer to be limited by the appended claims rather than by the foregoing description.

What I claim is:

1. Yarn making apparatus comprising in combination, a non-rotatable hollow supporting spindle, a pulley rotatably supported thereon, a hollow spool carrying spindle carried by said pulley, a yarn tensioning arm on said spool carrying spindle arranged for frictional engagement therewith and a yarn guide cap above said spindle having a peripheral edge wall for guiding yarn from said spindle and a central aperture therethrough for receiving yarn passing through said spindles.

2. Yarn making apparatus comprising in combination, a non-rotatable hollow spindle, a member including a hollow spindle rotatable thereon for carrying a spool of yarn, a tension arm removably carried by said rotatable spindle including adjustable means for frictionally clutching the same to said spindle having means for receiving yarn unwound from a spool on said spindle, a guide member provided with an opening therethrough

for receiving a cord passing upwardly through said spindles and being in the form of a cup having depending walls the periphery of which is adapted to guide yarn from said tension device onto a cord passing upwardly therethrough. 70

3. Yarn making apparatus comprising in combination, a rail, a cup having walls extending upwardly from said rail and fixed thereto by a non-rotatable hollow spindle 75 passing through a lower wall of said cup, means associated with said spindle and rail for securing the former to the latter, a pulley having a hub rotatable on said spindle which extends downwardly within said cup and provided with an annular groove into which the walls of the cup extend, a hollow spindle carried by said pulley and a device adjacent the upper end of said spindle for receiving a cord from a spool which may be carried 80 by said last-named spindle. 85

4. Yarn making apparatus comprising in combination, a rail, a hollow spindle including upper rotatable and lower non-rotatable separable parts, the lower part being secured to a rail, a cup having a lower wall provided with an opening through which the lower part of said spindle extends and by which it is clamped to the said rail and including side walls which extend upwardly from said rail, a pulley secured to the upper part of said spindle having a hub rotatable in the non-rotatable part of said spindle which extends downwardly with the side walls of the cup and a belt receiving part extending downwardly towards said rail outside the walls of the cup and means at the upper end of the spindle for receiving a cord from a spool which may be carried by said spindle. 95

5. Yarn making apparatus comprising in combination, a rail, a cup having an apertured lower wall on said rail and side walls extending upwardly from said rail, a lower non-rotatable spindle having its lower end extending through the aperture of said lower wall of the cup and means for securing the same to the rail, a pulley having a hub extending into said cup provided with a bore for receiving said spindle through a part of its length and a part extending downwardly towards said rail outside the walls of said cup, a hollow spindle having its lower end fixed in the upper end of the bore of said spindle and a device adjacent the upper end of said upper spindle for receiving a cord from a spool which may be carried by said upper spindle. 100 110 115 120 125

In testimony whereof I affix my signature.

JAMES P. SHORROCK.
